WIDE BAND TRANSMITTING AND RECEIVING SYSTEM

De Witt Rugg Goddard, Riverhead, N. Y., assignor to Radio Corporation of America, a corporation of Delaware

Application March 7, 1941, Serial No. 382,175

3 Claims. (Cl. 250—6)

In certain systems in use for transmitting and receiving wide band widths such as are required for television the tuned circuits comprising the tank circuits of the transmitter are given a very low Q in order not to discriminate too greatly against the higher modulation frequencies. This does not permit an impedance of over a few hundred ohms to be built up in the tank circuits, with the result that little power can be realized with the present transmitting tubes available. The use of the low Q circuits necessary to accommodate the wide band of television signals as a consequence results in rather poor power efficiencies.

Certain wide band width receivers such as are used for television have a similar trouble. The intermediate frequency coupling transformers in order to have a reasonably flat characteristic over the required band width of several megacycles must be loaded to such an extent that with the receiving tubes at present available, a low gain per stage is all that can be realized.

My system provides a method of radiating almost any reasonable power at several times the band widths already in use in television systems. Also in my system the difficulty of emitting large amounts of power at frequencies of several hundred megacycles is materially reduced.

In describing my invention reference will be made to the attached drawing wherein:

Figure 1 illustrates schematically a wide band transmitter such as, for example, a television transmitter arranged in accordance with my invention;

Figure 2 illustrates schematically a wide band receiver such as, for example, a television signal receiver arranged in accordance with my invention; while

Figure 3 illustrates a modification of the arrangement of Figure 2.

My invention comprises a transmitting and receiving system in which tubes at present available may be used with greater efficiency and almost any band width may be handled.

A transmitter arranged in accordance with my invention consists primarily of a system in which several power amplifiers combine their efforts in such a way that each power amplifier is required to pass but a fraction of the total band width radiated.

Let us assume that it is required to radiate a carrier at 60 megacycles with up to 3 megacycles of modulation, that is, modulated energy covering about 6 megacycles. To simplify the description let us further assume that but one set of side bands is to be radiated, let us say on the high frequency side of the carrier. Now, referring to Figure 1, a high frequency oscillator 10 of low power is modulated by, say television signals by way of the modulator 12 in the cus-

tomary fashion. The output of this oscillator which may be of low power is fed to the non-inductive resistor R. This can all be accomplished without difficulty, and in doing so high gain, low capacity receiving tubes may be used. Across R appears the 60 megacycle carrier together with a complete set of upper and lower side bands. Across R is connected radio frequency band-pass filter #1 passing frequencies from 60.0 megacycles to 61.0 megacycles. This filter preferably passes the 60.0 megacycle carrier and all the upper side bands between 60.0 and 61.0 megacycles. Also across R is connected filters #2 and #3 passing frequencies between 61.0 and 62.0 megacycles and 62.0 and 63.0 megacycles respectively. The outputs of these filters pass to power amplifiers Nos. P. A. 1, 2, and 3 as shown. These power amplifiers radiate their power through antennas 1, 2 and 3, respectively.

The signal that is passed into the ether from the above arrangement is no different from that of a single transmitter radiating 3 megacycles of modulation on a 60 megacycle carrier with the lower side band suppressed. However, the above system would radiate three times the power and each power amplifier is required to handle but 1 megacycle of modulation. In practice greater efficiency than heretofore obtainable is realized because, due to the narrower band of frequencies passed by each channel, higher impedances may be built up in the transmitter filter and amplifier tank circuits. It is not necessary to make the filters divide the modulation band equally. As most of the power is concentrated in the carrier and the side bands close to it, it is in some cases preferable to have filter #1 pass, say, 60 to 60.5 megacycles, filter #2 pass 60.5 to 61.5 megacycles and filter #3 pass 61.5 to 63 megacycles. An arrangement of this nature provides a maximum of efficiency.

It will be understood that in selecting a modulation frequency band of three megacycles applicant does not thereby limit his arrangement to the use of a band of modulation of this width. My invention is applicable to a narrower modulation band and is particularly applicable to a wider modulation band such as, for example, a 9 megacycle band of video signals used in television. The need of my arrangement grows with the modulation band width.

Where a 9 megacycle modulation band is used the filters #1, #2 and #3 may each pass one-third of the band covered by the carrier and one of its side bands, or, as in the example given above, the filters may have widths which increase as the frequencies passed thereby depart from the carrier frequency.

In a modification unit 10 may include, in addition to the modulator, a selective system for selecting out the carrier and one side band and sup-

plying the same to the resistance R from which adjacent and overlapping bands of frequencies, making up the carrier and selected side band, are supplied to the filters #1, #2 and #3.

The filters #1, #2 and #3 may be of any known approved type. Preferably in these filters I use concentric pipe inductances because filter circuits having Q 's of several thousand may easily be arranged with such reactances on ultra high frequencies. Preferably I use a filter that does not cause serious phase distortion, and of course, the filters have to overlap exactly the correct amount. The filters may be in several sections with opposed phase distortion characteristics which compensate.

Another item of importance is the location of the antennas. These should have exactly the same geographical location in order to present a uniform field without phase discrimination between the three component parts. This effect can be accomplished in two ways, either a single antenna may be substituted for the three shown in Figure 1 and each of the three power amplifiers P. A. #1, #2 and #3 coupled to it or three antennas, #1, #2 and #3, each consisting of a plurality of radiating members, all three being arranged about a single vertical axis, may be used.

It should be mentioned that the original signal need not necessarily be split up into three components. It may be split into two or four components, or as many as economy and power requirements dictate.

The receiving system to be outlined is in theory similar to the transmitter in so far as it splits the signal to be received into two or more parts, deals with each part independently and later combines them to produce the desired result. This has several advantages in receiver design. In the first place the problem of producing an intermediate frequency amplifier having high gain and a substantially flat band-pass of 3 megacycles is difficult with the tubes now available. An intermediate frequency amplifier to pass 4 or 5 megacycles would present a still greater problem as the gain per stage would be low due to the low plate impedances that can be built up.

Figure 2 shows an arrangement in which the antenna 20 and oscillator 26 feed the first detector 30 to produce the intermediate frequency output. This output is passed to the input of three intermediate frequency amplifiers, IF #1, #2 and #3. Each intermediate frequency amplifier amplifies a part of the total received signal and the output of the three amplifiers passes to a single second detector or demodulator 36. Here as in the transmitters the several amplifier circuits each are subjected to a narrower band of frequencies and as a consequence the circuits may be of higher Q and the amplifiers operate more efficiently and at higher frequencies.

If we assume the signal already described is to be received, then intermediate frequency amplifier #1 may be adjusted to amplify the band from 60.0 to 61.0 megacycles, thus taking care of the incoming carrier and one third of the side bands. Intermediate frequency amplifiers #2 and #3 are adjusted to pass the bands between 61.0 to 62.0 and 62.0 to 63.0 megacycles, thus taking care of the remainder of the transmitted band. The outputs of the three intermediate frequency amplifiers are connected to a single demodulator 36 the output of which is the desired 3 megacycles of modulation.

Another arrangement is shown in Figure 3. Here three antennas 40, 42 and 44 are connected to three radio frequency amplifiers RF #1, RF #2 and RF #3, each of which connects to its first detector (Det. #1, #2 and #3) which is also fed from a common oscillator 50. The output of each of these detectors is fed to an intermediate frequency amplifier, IF #1, #2 and #3. The output of these three intermediate frequency amplifiers feeds a common demodulator 56 from which is delivered the required modulation. The arrangement of filter band pass frequencies may be the same as in the receiver of Figure 2. This arrangement, however, provides for the utilization of three antennas, each of which operates at improved efficiency due to the narrower band of response required of it. This is particularly true where each antenna is a directive antenna. The antenna locations are of phase limitations as the antennas are "phased up" for any specific signal by adjusting the length of the transmission lines between the antennas and the radio frequency units.

It might be added that of course ordinary receivers may be used with the special transmitter outlined or an ordinary transmitter used with the above-described receiver. Also, in the case of transmission to a single receiving station transmitting antennas may be spaced any desired distance and their respective phases adjusted by varying the length of the transmission line feeding the antennas.

I claim:

1. In a signalling system, a source of wave energy, a source of signalling potentials covering a wide range of frequencies, low power modulating means for modulating the wave energy in accordance with said potentials, an impedance coupled to said last-named means, a plurality of filters having overlapping band pass characteristics and having inputs and outputs, means coupling the inputs of said filters in shunt to said impedance, a power amplifier coupled to the output of each filter and utilizing means coupled to the power amplifiers.

2. In a system for demodulating a wind band of high frequency wave energy comprising a carrier and side band frequencies, a plurality of filters each passing a different band of said high frequency wave energy, said filters together passing the entire band of frequencies, a source of oscillations, a frequency converter coupled to each filter, a coupling between each converter and said source of oscillations for heterodyning the bands of wave energy passed by the respective filters to corresponding bands of wave energy of lower frequency, a filter for passing a different band of frequencies coupled to each of said frequency converters and signal demodulating means coupled to all of said last named filters.

3. In a signalling system, a source of wave energy of carrier wave frequency, a source of signals covering a wide range of frequencies, a low power modulator for modulating the wave energy in accordance with said signals, said modulator having an output, a resistance connected to said output, a plurality of wave filters having overlapping band-pass characteristics and having inputs and outputs, connections coupling the inputs of said filters in shunt to said resistance, and wave amplifying means coupled to the output of each filter.

DE WITT RUGG GODDARD.
